Primary Examiner — George J Ulsh

Assistant Examiner — Kathryn Elizabeth Zieno

(74) Attorney, Agent, or Firm — Quarles & Brady LLP;
 James J. Aquilina(57) **CLAIM**

The ornamental design for a valve sleeve, as shown and described.

DESCRIPTION

FIG. 1 is a perspective view.

FIG. 2 is a top view.

FIG. 3 is a front side view.

FIG. 4 is a bottom view.

FIG. 5 is a cross sectional view taken from lines 5-5 in FIG. 2; and,

FIG. 6 is a close-up cross sectional view taken from lines 5-5 in FIG. 2.

The dot-dash broken line indicates cutoff boundaries for enlarged detailed portion views and form no part of the claim.
